HOSE SUPPORTING DEVICE

Thomas A. Conley, Harrisville, R. I., assignor to
 American Optical Company, Southbridge,
 Mass., a voluntary association of Massachusetts

Application February 8, 1950, Serial No. 143,087

1 Claim. (Cl. 224—5)

1
 This invention relates to supporting devices and has particular reference to devices adapted for use in securing objects such as hoses to supporting means therefor.

In the manufacture of air supply devices of the kind embodying a central plant having a plurality of hoses leading therefrom to respective respirators or similar masks to be worn by a corresponding number of users, it is generally necessary to provide each hose with a valve adjacent each mask or respirator so that the wearer can independently control the flow of air from the central plant into his mask. However, it has been found that such valve mechanisms are generally of substantial weight which, when combined with the weight of the hose and couplings, will tend to render the mask or respirator uncomfortably heavy when worn on the face of an individual or may even cause the mask to become disengaged from the face of the wearer, breaking the air seal. There is also the important disadvantage present in such arrangements that the added weight may cause a hose to become disconnected from a valve coupling or that the valve may be accidentally operated, with possible serious results with respect to the health of the user.

Therefore, it is a principal object of this invention to provide a device for supporting an air supply hose in attached relation to the body of a user whereby the weight thereof will be absorbed by the device with resultant increase in life of the hose and efficiency of operation and control of the air supply system.

Another object is to provide a supporting device of the above character embodying a holster shaped to be carried on the waist belt of the user and comprising a portion shaped to resiliently encircle a hose adjacent the valve to retain it in position near the body of the user and having an opening therein through which the valve may extend, with said opening being elongated to permit the hose and valve to be turned within the encircling portion to a position where the valve may be easily operated.

Another object is to provide a device of the above character in which the elongated opening in the resilient hose-encircling portion is so located as to permit the valve to extend, when in a normal position, upwardly in a direction substantially parallel to the body of the user and adjacent thereto and which will permit the valve to be turned downwardly within the limits of the elongated opening so as to extend outwardly at an angle from the user's body where it may be easily operated for control of the air supply passing to the user's mask or respirator.

2

Another object is to provide a device of the above character which is simple in its construction, efficient in its use, and relatively economical to manufacture.

5 Other objects and advantages of the invention will become apparent from the following description taken in connection with the accompanying drawing, in which:

Fig. 1 is a fragmentary front elevational view 10 of an embodiment of the invention shown in position of use; and

Fig. 2 is a side elevational view, partly in section, of the embodiment shown in Fig. 1.

Referring to the drawing wherein like characters of reference designate like parts throughout the several views, a clip or holster 10 embodying the invention is shown as applied to a waist belt 11 of a user, and is comprised initially of a flat, elongated strip of metal of a resilient nature 15 such as spring steel or the like. The strip of metal is formed with a bend as at 12 so as to provide a rear, downwardly extending portion 13 adapted to be positioned adjacent the rear surface of the belt 11 and a frontal portion 14 extending downwardly parallel to the rear portion 13 for engaging the front surface of the belt 11, which portions 13 and 14 are continually urged toward each other by the inherent resiliency of the material and may be spread apart to receive therebetween the belt 11 of the user. The lower end of the front portion 14 is provided with an outwardly protruding curved portion 15 which is adapted to encircle a valve coupling 16. The coupling 16 has attached to one side thereof one end of a flexible hose 17 leading to the mask or respirator (not shown) of the user and has attached to its opposed side a hose 17a leading to a conventional air supply plant.

Since it is most desirable to support the hose line at or adjacent the point of greatest weight, the encircling portion 15 is adapted to resiliently encircle the coupling 16 and is provided with an elongated, vertically extending slot 18 through which the valve control mechanism 19 is adapted to extend. The valve control mechanism 19 is formed with a shaft 20 which is adapted to extend into the coupling 16 through a boss or extension 21 formed on the coupling to control conventional valve mechanism 21a within the coupling, the boss 21 being of a diameter substantially equal to the width of the slot 18 to prevent the coupling from pulling out of the holster.

The conventional packing nut 22 and operating knob 23 are assembled subsequent to the attachment of the holster to the coupling, the knob 23 being attached by suitable means such as a screw

or the like to the shaft 20 to control the operation of the valve mechanism 21a within the coupling.

As shown in the drawing, the valve control mechanism 19 can be normally carried in an upright position adjacent the frontal portion 14 of the holster 10 and substantially parallel to the body of the wearer where it will be less apt to become accidentally operated as it might if it was located so as to extend outwardly. However, since it is much easier to operate the control mechanism 19 if it is angled outwardly with respect to the frontal portion 14 of the clip, the elongated slot 18 has been provided so that the valve control mechanism 19 may be grasped by the user and turned within the encircling portion 15 of the clip 10 to a position as shown in dotted outline in Fig. 2 where it may be more easily operated. It is to be understood that such movement of the valve device is confined to the extent of movement permitted the boss 21 by the slot 18 and is against the tension exerted by the inherent resiliency of the material of the encircling portion 15. Subsequent to the operation of the control mechanism 19, the valve device can be turned in the opposite direction within the encircling portion 15 and thus returned to the normal initial position.

With such a construction it is quite evident that since the device is supported at the point of greatest weight, there will be less likelihood of the hoses 17 and 17a becoming disconnected from the coupling 16 and thereby rendering the air supply system inefficient. Also, by reducing the total or overall weight carried by the mask or respirator when in position of use on the face of the user, this will result in increased efficiency of the mask or respirator since such added weight will not tend to cause the mask or respirator to become disengaged from the face of the wearer.

From the foregoing it will be seen that simple, efficient and economical means have been provided for accomplishing all of the objects and advantages of the invention by providing a clip or holster which is adapted to be positioned on the waist belt of a user and which is adapted to resiliently support a hose at or adjacent the valve control mechanism, with means being provided for controlling movement of the valve control mechanism into and out of a position where it may be more easily operated.

While the novel features of the invention have been shown and described and are pointed out

in the annexed claim, it will be understood that many changes may be made in the details of construction shown and described without departing from the spirit of the invention. I, therefore, do not wish to be limited to the exact details shown and described as the preferred only are set forth by way of illustration.

I claim:

A holster for use in supporting the valve of an air supply hose in attached relation to the body of a user wherein the valve includes a coupling and control mechanism protruding from one side thereof, said holster being formed of a single strip of resilient material having one end portion folded transversely of its longitudinal axis to form a pair of substantially parallel front and rear flat portions continually urged toward each other by the inherent resiliency of the material and adapted to be spread apart to resiliently engage a portion of the wearer's belt when inserted therebetween, and the other end portion of said strip being curved forwardly and outwardly of the front one of said parallel flat portions and thence downwardly and upwardly in the form of an arc constituting the greater part of a circle, substantially all of said holster including said curved end portion being located forwardly of the plane of the rear one of said flat portions so that the holster may fit comfortably on the wearer when in position of use, and said curved end portion having a diameter less than that of the valve coupling to be inserted therein so that the coupling will be resiliently held in place thereby, said curved end portion having an elongated slot on its forward side extending in the direction of the length thereof permitting the control mechanism of said valve to be extended therethrough, and said slot being of a length to permit convenient angling of said control mechanism to different positions when said valve is in assembled relation with the holster.
